US00D747797S

(12) **United States Design Patent**
Fourt et al.

(10) **Patent No.:** **US D747,797 S**
(45) **Date of Patent:** **** Jan. 19, 2016**

(54) **INJECTION DEVICE**

(71) Applicants: **Jesse Arnold Fourt**, Menlo Park, CA (US); **Alexander Coriano, III**, Brisbane, CA (US); **John W. Lai**, San Bruno, CA (US); **David Jason Wilkins**, San Francisco, CA (US); **Thomas Dieter Christian Overthun**, San Francisco, CA (US)

(72) Inventors: **Jesse Arnold Fourt**, Menlo Park, CA (US); **Alexander Coriano, III**, Brisbane, CA (US); **John W. Lai**, San Bruno, CA (US); **David Jason Wilkins**, San Francisco, CA (US); **Thomas Dieter Christian Overthun**, San Francisco, CA (US)

(73) Assignee: **Eli Lilly and Company**, Indianapolis, IN (US)

(**) Term: **14 Years**

(21) Appl. No.: **29/472,626**

(22) Filed: **Nov. 14, 2013**

(57) **CLAIM**

The ornamental design for an injection device, as shown and described.

DESCRIPTION

FIG. 1 is a perspective view of an injection device showing our new design;

FIG. 2 is a front view thereof;

FIG. 3 is a rear view thereof;

FIG. 4 is side view thereof;

FIG. 5 is an opposite side view thereof;

FIG. 6 is a top view thereof; and,

FIG. 7 is a bottom view thereof.

The broken lines in the Figures showing an internal portion and features on an underside of a middle portion and features on a bottom portion of the injection device form no part of the claimed design.

1 Claim, 6 Drawing Sheets
